LIFTING MAGNETS

Howard E. Hodgson, Wauwatosa, Wis., assignor to Cutler-Hammer, Inc., Milwaukee, Wis., a corporation of Delaware

Application October 9, 1953, Serial No. 385,137

7 Claims. (Cl. 317—158)

This invention relates to improvements in lifting-magnets and methods of making the same. More specifically, it relates to means for interlocking the magnet winding and the magnet core, and to methods of making an electromagnet employing such interlock means.

Heretofore, a source of trouble frequently encountered in the use of lifting-magnets has been excessive movement between the magnet core and the magnet winding. Such movement has often resulted in broken or shorted leads, thus incapacitating the magnet until the necessary repairs could be made.

Such undesirable movement between the magnet winding and core usually occurs in electromagnets which are subjected to frequent rotative movement during normal use. Such is the case with lifting-magnets which are subjected to many torsional shocks and strains in the course of a day's work.

The primary object of this invention is to provide a lifting-magnet which will readily withstand the shocks and strains to which it is normally subjected.

Another object is to provide a method of winding a lifting-magnet; which method provides interlocking the magnet winding with the magnet core to prevent relative rotational movement therebetween.

Another object is to provide simple and inexpensive means for positively retaining the magnet winding in a given position with respect to the fixed magnet parts.

Another object is to provide an efficient lifting-magnet which will withstand severe service and obviate the necessity for constant repair.

Other objects and advantages of the invention will become apparent from the following description of a specific embodiment when read in connection with the accompanying drawings, in which:

Figure 1 is a fragmentary view of the core and winding of a lifting-magnet embodying my invention;

Fig. 2 is a fragmentary sectional view, taken along the line 2—2 of Fig. 1, and

Fig. 3 is a fragmentary sectional view, taken along the line 3—3 of Fig. 1.

Like reference characters indicate corresponding parts throughout the several views of the drawings.

Referring to the drawings, they show a magnet core 10 having a outer periphery 10^a. Attached to said outer periphery 10^a of core 10 is a pair of keys 12 each of which is held in place by several studs 14 press-fitted into engagement with recesses 10^b in core 10. As shown in Fig. 1, keys 12 are circumferentially spaced a suitable distance from each other on periphery 10^a.

After fastening of said keys 12 to core 10, several complete turns of insulating sheet material such as mica are wound on the outer periphery of core 10. Although not essential to successful operation of the present invention, I prefer to use only a portion of a complete turn of insulating material against the core. Thus insulating strip 16 extends from the outer side of one of the pair of keys 12 to the outer side of the other one of said keys.

2

Between said keys 12, and having its intermediate portion resting against said outer periphery 10^a, is a small strip 16^a of insulating material which bridges and overlaps said keys as shown in Fig. 1. Wound around said strips 16 and 16^a are one or more complete turns 16^b of insulating material. Although not necessary to successful operation of this invention, I prefer to subject insulating strips 16 and 16^a and turns 16^b to a reasonable amount of heat to thereby improve the formability thereof while being positioned shown in Fig. 1. Such strips and turns are thus caused to follow very closely the irregularities created by keys 12.

Wound around said complete turns 16^b of insulating material are a suitable number of complete turns 18 of magnet winding material comprising copper strips 18^a and any suitable insulating material such as asbestos paper 18^b. As shown in Fig. 1, I prefer to wind one of the copper strips 18^a against the complete turns 16^b of insulating material and thereafter continuing the winding of copper strips 18^a together with asbestos paper 18^b so that each complete turn of copper strip is insulated from adjacent turns of copper strip by the asbestos paper.

An insulating spacer block 20 is then positioned against the several complete turns of magnet winding material between keys 12 as shown in Fig. 1. That is, block 20 is circumferentially positioned with respect to core 10 so that said block 20 is intermediate the keys 12. Block 20 is forced against said magnet windings 18 by any suitable method to thus increase the interlocking of keys 12 with the entire winding.

A suitable number of insulating strips 22 are then positioned against the several complete turns 18 of magnet winding material as shown in Fig. 1 to thus effect the desired contour of the magnet winding and to assist in preventing the undesirable slippage.

Following positioning of block 20 and insulating strips 22, complete turns 24 of magnet winding material necessary to provide the desired number of ampere turns are then tightly wound on the core. Said complete turns 24 press insulating block 20 against the several complete turns 18 of magnet winding material, thus causing the small insulating strip 16^b to bind against keys 12. Such binding action thus prevents any substantial degree of relative movement between the completed magnet winding and the magnet core.

As shown in Figs. 2 and 3, it is often desirable to use several complete magnet windings on the same magnet core. In this event, each of the magnet windings is insulated from adjacent windings by insulating discs 26. If the electrical potential difference between adjacent windings is quite large due to the manner in which the windings are connected, I then prefer to employ insulating strips 28, each of which is of L-shape in cross section as shown in Figs. 2 and 3. Insulating strips 30 are employed in size and number in accordance with the electrical potentials to be encountered.

Although I use keys 12 which extend across the several magnet windings used (Fig. 2), I prefer to employ individual insulating spacer blocks 20 for each winding because of the variation in size of the insulating and magnet winding materials and to permit the use of discs 26 for completely insulating adjacent windings from each other.

Although I have shown and described a specific embodiment of my invention, I am fully aware that many modifications thereof are possible. My invention, therefore, is not to be restricted except in so far as is necessitated by the prior art.

70 I claim:

1. For use in an electromagnet, in combination, a magnet core, a pair of keys spaced from each other on said

magnet core, a plurality of turns of magnet winding on said core and over said keys, and a spacer positioned between said keys and pressed inwardly of said core between adjacent turn layers of said plurality of turns of said magnet winding to interlock underlying layers of turns with said keys to restrain said magnet winding against slippage on said magnet core.

2. For use in an electromagnet, in combination, a magnet core having a peripheral surface, a pair of keys positioned on said peripheral surface and providing a space therebetween, a plurality of turns of magnet winding on said core and over said keys, and a spacer positioned at least partly within said space between said keys and being pressed inwardly of said core between adjacent turn layers of said plurality of turns of magnet winding to interlock underlying turn layers to said keys to prevent substantial relative movement between said magnet winding and said magnet core.

3. For use in an electromagnet, in combination, a cylindrically shaped magnet core, a pair of keys circumferentially positioned from each other on said core, a plurality of turns of magnet winding on said magnet core and said keys, and a spacer circumferentially positioned between said keys with respect to said magnet core, said spacer being pressed inwardly of said core between adjacent layers of turns of said plurality of turns to press underlying layers of turns into interlocking engagement with said keys to thereby prevent relative movement between said magnet winding and said core.

4. For use in an electromagnet, in combination, a cylindrically shaped magnet core, a pair of keys circumferentially spaced from each other on said magnet core, at least one complete turn of insulating winding on said magnet core and over said keys, at least one complete turn of magnet winding on said insulating winding, an insulating spacer pressed inwardly on said magnet winding between said keys, insulating filler also on said aforementioned magnet winding to provide the desired contour, and additional turns of magnet winding on said insulating spacer and filler providing the desired total winding turns and holding said spacer pressed as aforescribed to interlock the magnet winding with said keys to prevent relative movement therebetween.

5. For use in an electromagnet, in combination, a cylindrically shaped magnet core, a pair of keys circumferentially spaced from each other on said core, each of said keys having an edge parallel to the axis of said

cylindrically shaped core, a plurality of turns of magnet winding on said magnet core and said keys, and a spacer circumferentially positioned between said keys and lying between adjacent turn layers of said plurality of turns and held pressed inwardly toward said core by overlying turn layers to interlock underlying turn layers with said edges of said keys to prevent relative movement between said magnet winding and said core.

6. For use in an electromagnet, in combination, a cylindrically shaped magnet core, a pair of keys circumferentially positioned from each other on said magnet core, each of said keys having an edge parallel to the axis of said cylindrically shaped core, at least one complete turn of insulating winding on said magnet core and over said keys, at least one complete turn of magnet winding on said insulating winding, an insulating spacer on said aforementioned magnet winding circumferentially located between said keys, insulating filler also on said aforementioned magnet winding to provide the desired contour, and additional turns of magnet winding on said insulating spacer and filler to provide the desired number of total winding turns, said additional turns pressing said spacer inwardly toward said magnet core to interlock underlying layers of the magnet winding with said edges on said keys to prevent relative movement therebetween.

7. For use in an electromagnet, in combination, a magnet core provided with means comprising spaced apart opposing shoulders, a plurality of magnet winding turns on said core over said shoulders, and a spacer positioned between said shoulders and pressed inwardly of said core between adjacent turn layers of said winding to interlock underlying layers of said turns with said keys to restrain said magnet winding against slippage on said magnet core.
